UNITED STATES PATENT OFFICE.

THOMAS H. RHODES, OF BROOKLYN, NEW YORK.

ELECTRICAL GAS-LIGHTING APPARATUS.

SPECIFICATION forming part of Letters Patent No. 257,070, dated April 25, 1882.

Application filed March 13, 1882. (No model.)

To all whom it may concern:

Be it known that I, THOMAS H. RHODES, of Brooklyn, in the county of Kings and State of New York, have invented an Improvement in 5 Electric Gas-Lighting Apparatus, of which the following is a specification.

Gas-burner cocks have been operated by an electric current acting on an electro-magnet to turn the cock, and at the same time a spark 10 has been drawn for the ignition of the gas.

In my improvement I employ a sliding valve which is acted upon by the armature of one magnet to move such valve in one direction and open the gasway, or by another magnet to move the valve in the other direction and close the gasway. I provide a spring-arm 15 that is operated by the electro-magnet for producing a spark, and I arrange the circuits in such a manner that a thermal circuit-closer 20 makes connection while the gas is burning with the magnet that acts to close the cock when a current is sent over the line for that purpose.

In the drawings, Figure 1 is an elevation of 25 the burner and the magnet that closes the gas way or tube. Fig. 2 is a similar view of the magnet that opens the gas-tube. Fig. 3 is an elevation at right angles to Figs. 1 and 2. Fig. 4 is a section of the cock and gasway, and 30 Figs. 5 and 6 are diagrams of the circuit-connections.

The gas-burner *a* is at the end of the gas-tube *b*. This is attached to any ordinary gas-pipe on a chandelier, bracket, lamp-post, or any 35 gas-fixture. In the gas-tube *b* there is a transverse hole that contains a sliding valve, *c*. Said valve may be cylindrical or prismatic, and may have a hole through it to form the gasway; but I prefer to have a groove or neck turned 40 in it, as shown in Fig. 4. The end motion to this valve is limited by heads or flanges at each end. When this valve is pushed in one direction, as seen in Fig. 4, the groove corresponds with the tubular gasway *b* and allows 45 the gas to pass; but when the valve is moved endwise the other way into the positions shown in Figs. 1 and 2 the gasway is closed by the plug-valve filling the gasway.

I employ the electro-magnet *f* to move the 50 valve to open the gas-pipe and the magnet *g* to close it. These magnets are of ordinary

character, and the respective armatures *f'* and *g'* are provided with arms or fingers that are at opposite ends of the valve *c*. The spark-points *h* and *i* are in the circuit of the magnet *f*. The point *i* is upon a lever pivoted at *s*, and the lower end is bent toward the armature *f'*, so that when the electric current has been sent over the wires or conductors it energizes the magnet *f*, attracts the armature *f'*, moves the 60 valve endwise, opens the gasway to the burner, and then the armature, when close to the magnet, exerts its force to overcome the spring of the arm *i* and separate the points and produce a spark to ignite the gas. This movement of the spark-point breaks the circuit to the magnet *f*, the armature falls back, the spark-points close, and the magnet is again energized and draws the spark, and so on as long as the current is continued until the gas 70 is lighted and the current is shunted, as hereinafter set forth.

I employ a thermal spring, *r*, in the circuit leading to the magnet *f*, the same being placed between the posts 1 and 2, and the bow of the 75 spring *r* is at the base of the flame, so that it will become warm and expand sufficiently to cause the loose end of such thermal spring to leave the post 2 and form a contact with the post at point 3. This contact will be maintained so long as the gas is burning. I use 80 this thermal spring as a switch, so that the electric circuit will be broken at 2 and closed at 3. This thermal switch is available for 85 ringing a burglar or other alarm, as hereinabove shown; but if it is only employed in circuits for lighting and extinguishing the gas there will be a wire between the post 3 and magnet *g*, as shown in Fig. 3 and by the dotted line, Fig. 5, so that if a current is sent over the electric circuit after the heat of the flame has expanded the spring *r* it will go by 1 *r* 3 to *g*, and thence to ground, preferably by the gas-pipe itself, and by energizing the magnet *g* the armature *g'* will be moved to cause the 90 valve *c* to close the gas-pipe and extinguish the flame. It is to be borne in mind that with these circuit-connections the current must be interrupted as soon as the gas is lighted and only connected in the circuit when the gas is 100 to be extinguished; otherwise the expansion of the spring *r* by the heat would switch the

current through g and immediately put out the light.

It is preferable to connect the ground or return circuit of both magnets, f and g , to the 5 gas-pipe.

A limited number of burners, fitted as aforesaid, may be in one circuit, there being branches from that circuit to the respective burners. When the circuit passes to the binding-post 1 10 and continues from the binding-post 3 to the next burner, and so on, as indicated by the diagram, Fig. 6, any desired number of lamps may be placed in circuit, because after one lamp is lighted the thermal spring closes the 15 circuit to the next lamp and cuts out the magnet at its own lamp. In this case the lamps can be extinguished by a separate line-wire to the extinguishing-magnets g , as shown in Fig. 6.

In dwelling-houses it is often desirable to 20 connect the gas-burner with a burglar-alarm or with a circuit-closer operated automatically, so that on opening a door or window the gas may be ignited. To effect these objects I have represented in the diagram, Fig. 5, a battery 25 at v and circuit-closers at p and q . These circuit-closers may be operated automatically in connection with burglar-alarms, or they may be operated by hand. The circuit-closer p is represented as self-closing when the door v' is 30 swung open. When the circuit is closed at p the current energizes the magnet f and lights the gas, as aforesaid. When the circuit is closed at q the magnet g acts to extinguish the gas, the current passing from v , by q and g , to 35 ground and returns to battery. When the circuits are connected up, as seen in Fig. 5, the thermal spring will act as soon as the gas is lighted to close the circuit to the bell or other alarm at w , and this should be closed on the 40 back stop of the armature, so as to keep up an alarm until the circuit is broken, which may be effected by the switch at x .

A push-button, u , placed in the circuit to the burner, allows the gas to be lighted by hand.

45 The automatic circuit-closers may be more or less numerous and connected in circuits similar to those in burglar-alarms. The connections shown in the diagrams serve to illustrate the general mode of applying the circuit- 50 closers.

I do not in this application lay any claim to a valve having a seat and moved endwise by the action of one or more magnets. In my improvement the valve, being parallel-sided, has no seat, and it opens and closes the gasway 55 without requiring any pressure to hold the valve tightly to its place. The valve may have more or less motion, and its momentum under the sudden action of an electro-magnet will insure a complete movement in either direction, 60 so as to entirely open or shut the gasway.

I claim as my invention—

1. The combination, with a gas-burner, of a sliding parallel-sided valve passing across and acting to open and close the gasway, and two 65 electro-magnets and their armatures acting at opposite ends of the valve to move it in either direction, substantially as set forth.

2. The combination, with the gas-burner, sliding valve, and two electro-magnets and their 70 armatures for actuating the valve, of a thermostatic circuit-closer acting to divert the circuit-connection from the igniting-magnet to the extinguishing-magnet, substantially as set forth.

3. The combination, with the magnet and burner in an electric gas-lighting apparatus, of a sliding parallel-sided valve with a groove or neck thereon, adapted to move transversely 75 across the pipe and open and close the gas- 80 way; substantially as set forth.

4. The combination, with the gas-burner, of the sliding valve, the magnet f , and armature f' for opening the valve, and the spark-points h and i , the latter of which is moved by the armature f' , substantially as set forth. 85

5. The combination, with the gas-burner and the sliding valve, of the two electro-magnets, one to open the gasway, the other to close it, a thermal switch to change the circuit-connections when the gas is burning, and local circuit-connections and circuit-closers p q , substantially 90 as set forth.

Signed by me this 9th day of March, A. D. 1882.

THOS. H. RHODES.
